OR

6-722

UNITED STATES PATENT OFFICE.

THOMAS W. MOORE AND FREDERICK M. MOORE, OF NEW YORK, N. Y.

DESIGN FOR FURNITURE.

Specification forming part of Design No. 6,722, dated June 24, 1873; application filed June 14, 1873.

To all whom it may concern:

Be it known that we, THOMAS W. MOORE and FREDERICK M. MOORE, of the city, county, and State of New York, have invented a new and original Design for Furniture, of which the following is a specification:

Figure 1 of the accompanying photographic illustrations represents my design for furniture complete, and Fig. 2 represents one of the handles on an enlarged scale to illustrate the form more clearly.

Similar letters of reference indicate corresponding parts.

The first part consists of the design A, placed midway on the top of the straight pieces forming the Gothic part of the head of the bedstead. The second part consists of the extension B, running down from the shield in the center of the head-board from the top. The third part consists of the round cap C of the posts of the bedstead and the glass-frame. The fourth part consists of the oval-raised figure on the sides of the top of the posts at D, and at G in other parts. The fifth part

consists of the antique urn-shaped figure on the top of the parts, as represented at E. The sixth part consists of the form of the part F, which constitutes the lower top piece of the Gothic top of the head piece of the bedstead, and the frame of the glass. The seventh part consists of the form of the ornaments H on the panel and frame of the wash-stand. The eighth part consists of the urn-shaped cups I on the glass-frame. The ninth part consists of the pieces K on the sides of the lower ends of the posts of the head-frame. The tenth part consists of the form of the drawer-knobs L, either with or without the curved stem.

We claim as our design for furniture—
The several features hereinbefore described, each separately and specifically as set forth in the several clauses numbered one to ten inclusive.

THOMAS W. MOORE.
FREDERICK M. MOORE.
